JOSEPH R. BARTLETT, OF KANSAS CITY, MISSOURI; MARGARET M. BARTLETT, ADMINISTRATRIX OF SAID JOSEPH R. BARTLETT, DECEASED, ASSIGNOR TO MARGARET M. BARTLETT, OF KANSAS CITY, MISSOURI.

BAG PACKING AND SEWING MACHINE.

Application filed July 17, 1926. Serial No. 123,050.

My invention relates to bag packing and sewing machines and more particularly to one for use in flour mills for packing and sewing bags of flour.

5 It is the principal object of my invention to provide a bag packing and sewing machine by which flour or other material may be properly packed in bags and the bags sewed with a stitch corresponding to that employed in 10 hand sewing and with which the string may be easily and quickly severed and removed without damage to the bag.

In accomplishing this and other objects of the invention I have provided improved 15 details of structure, the preferred forms of which are illustrated in the accompanying drawings wherein:—

Fig. 1 is a side elevational view of a bag packing and sewing machine constructed according to my invention.

Fig. 2 is a plan view of the machine.

Fig. 3 is an end view of the machine.

Fig. 4 is a vertical, sectional view through the machine on the line 4—4, Fig. 2.

25 Fig. 5 is a detail sectional view through the turntable and one of the bag filling mandrels, illustrating the filling of a bag.

Fig. 6 is a detail, fragmentary view of one of the main drive gears, illustrating the stop for aligning the gear in its normal position.

30 Fig. 7 is a detail view, illustrating the position of the bag just before the packing piston pushes the bag off of its mandrel.

Fig. 8 is a similar view, illustrating the bag just after it has been removed from its mandrel and showing the bag engaged by the clamping jaws preparatory to the rolling of the top to close the bag.

Fig. 9 is a detail perspective view of the 40 string cutter.

Fig. 10 is a perspective view of the top roll forming clamps, the needle and the ear tying disks in their normal positions.

Fig. 11 is a similar view showing the needle being driven through the roll formed at the top of the bag.

Fig. 12 is an enlarged detail perspective view of one of the string gripping jaws carried by the ear tying disks.

50 Fig. 13 is a detail elevational view, illustrating the needle at the end of its travel preparatory to drawing a string through the

roll formed at the top of the bag, the ear tying disks being in position to receive the ends of the string.

55

Fig. 14 is a similar view showing the string drawn through the bag and the string clamps on the ear tying disks engaging the ends of the string ready to tie the string.

Fig. 15 is a similar view, showing the tying 60 disks drawing the ends of the string taut to tie the ears formed on the bag.

Fig. 16 is an enlarged, detail sectional view through one of the bag gripping clamps.

Fig. 17 is a detail perspective view of the 65 end of the needle in position to engage the string.

Fig. 18 is a sectional view of the end of the needle and the string positioning reel, illustrating the needle just before it engages the 70 string.

Fig. 19 is a similar view illustrating the needle engaging the string.

Fig. 20 is a perspective view of a bag after it has been filled and sewed.

75

Referring more in detail to the drawings by numerals of reference:—

1 designates the frame of the machine consisting of side members 2 and 3 spaced apart and connected by a top frame member 4, a lower frame member 5 and an intermediate frame member 6, all preferably consisting of castings connected by bolts to form a rigid structure, and the side members 2 and 3 having flanges 2'—3' by which the frame may be anchored to the floor.

Supported within the frame by a bracket 7 (Fig. 4) on the side frame member 3 and extending vertically through the frame member 6 is a tubular stand 8 having a flange 9 at its upper end for supporting a turntable 10 (Figs. 1, 4 and 5). The turntable 10 comprises a disk 11 provided about its periphery with a plurality of openings 12 in which are suspended bag-receiving mandrels 13, each having a shoulder 14 at its upper end to engage the under side of the disk, the projecting ends of the mandrels being peened over the top face of the disk, as at 15, to anchor the mandrels to the disk. The mandrels 13 are hollow so that the bags may be filled therethrough from a delivery spout 16 (Fig. 3) opening in line with the upper end of the mandrels. As the bags are filled, they are ad-

vanced by the turntable and are supported from sliding off the mandrel by an arcuate table 17 supported by the frame member 6.

The turntable 10 is driven from a primary shaft 18 (Figs. 1, 3 and 4) mounted in bearings 19 and 20 carried by the frame side members 2 and 3. The shaft 18 is driven from a source of power (not shown) by a belt 21 running over a pulley 22 loosely mounted thereon, but adapted to drive the shaft through a clutch member 23 slidably keyed to the shaft by a key 24. The clutch member 23 is provided with teeth 25 engageable with complementary teeth 26 on the pulley 22, so that when the clutch member 23 is slid into engagement with the constantly driven pulley, the shaft will be driven as long as the sliding clutch member is held in engagement with the clutch member on the pulley. Pinned to the shaft is a bevel gear wheel 27 meshing with a bevel gear wheel 28 pinned to a vertical shaft 29 journalled in a bearing 30 on the frame member 5, and pinned to the shaft 29 is a segmental gear wheel 31 (Fig. 2) which meshes with a pinion 32 on a vertical shaft 33 rotatably mounted in the frame members 5 and 6.

The shaft 33 extends upwardly to adjacent the turntable 10 and carries a pinion 34 at its upper end. The pinion 34 engages teeth 35 on the periphery of the turntable 10 so that when the clutch is in, the turntable is rotated in a clockwise direction as designated by the arrow, Fig. 2. The clutch member 23 is controlled by a rod 36 slidably mounted in the side frame member 3 and carrying an arm 37 terminating in a fork 37' which engages in an annular groove 38 in the hub of the clutch member 25. The free end of the rod carries a roller 39 normally engaging in a notch 40 (Fig. 6) in a flange 41 on the bevel gear wheel 28 and held therein by an expansion spring 42 on the outer end of the rod, one end of the spring bearing against the side frame member 3 and the other against a head 43 carried on the end of the rod. Thus it will be seen that when the clutch is out, the gear wheel 28 will be locked from rotation, but when the rod is slid forwardly to "throw in" the clutch, the gear wheel 28 will be released. The gearing is so timed that during one-half revolution of the gear wheel 28 the turntable will advance one mandrel space in a clockwise direction. In the machine illustrated there are eight mandrels and the turntable advances 45 degrees each time the clutch is engaged.

Due to the segmental gear, the turntable is idle the other half revolution of the gear wheel 28 for a purpose hereinafter described.

After the bag is filled and the turntable advanced one space, the bag comes into alignment with a packer plunger 43 on a rod 44 slidable in a bearing 45 carried in the top frame 4 and the plunger is moved downward-

ly into the mandrel to pack the flour by an arm 47 integral with a collar 48 on the pinion 49 slidable vertically in the stand 8 about a stationary, vertical screw shaft 50 fixed between the bracket 7 and the top member 4 by a nut 51 which draws a shoulder 52 on the shaft against the member 4 to prevent rotation of the shaft.

The shaft 50 is provided with a spiral thread 53 which engages an internal thread 54 in the top of the pinion 49 so that as the pinion is rotated it is moved longitudinally to lower and raise the plunger to compress and pack the flour in the mandrel. This is an important feature for by packing flour in the mandrel instead of directly in the bag, liability of bursting the bag is eliminated as all the packing pressure is on the mandrel.

During the packing operation the toothed segment gear 31 has left the pinion 32 and the turntable 10 remains idle. At this time another bag is placed on an empty mandrel which has previously moved to position in front of the operator. The packing plunger is moved downwardly on the third quarter revolution of the bevel gear wheel 28 and up on the fourth or final one quarter revolution of the gear wheel by the following mechanism:

On the upper end of the shaft 29 is fixed a spur gear wheel 55 carrying a quarter segment of a gear 56 on its upper face (Fig. 3) which is adapted to mesh with a pinion 57 on a shaft 58 during a quarter revolution of the gear wheels 55 and 28. The shaft 58 is mounted on an extension 7' of the bracket 7 and in a bearing 6' in the horizontal frame member 6. Mounted upon the upper end of the shaft is a gear 59 which meshes with the elongated pinion 49 to cause the pinion to rotate and thread itself downwardly on the rod, carrying the plunger arm with it, packing the flour.

When the plunger reaches the end of its stroke, the pinion 57 is freed from its engagement with the segment 56 and is engaged by a quarter segment gear 61 to rotate it in the opposite direction, raising the plunger to its retracted position to permit a further advance of the turntable. The segment 61 is fixed on the face of a gear wheel 62, on a shaft 62' journalled in the frame member 5 and driven from the gear wheel 55 in a direction reverse to the gear wheel 55 which threads the elongated pinion upward.

In the machine illustrated, after four operations of the clutch, the first bag to be inserted reaches the discharge position where the filled bag is removed from the mandrel. Also carried by the collar 48 at the top of the elongated pinion is an arm 63 (Figs. 2, 7 and 8) which carries at its free end a discharging plunger 64 and at each side of the arm 63 are arms 65 and 66 carrying depending rods 67 and 68 which support a seat 69

in line with and at the end of the arcuate table 17 so that when the bags move off the ends of the table, they will rest on the seat 69. Therefore, when the elongated pinion 49 moves downward, it will also lower the ejector and at the same time the seat 69 to push the packed flour out of the mandrel and into the bag, the bag being lowered with the seat until the top of the bag comes into alignment with the top edges of the clamps 70 and 71 (Figs. 7 and 8) where the top edges of the bag are pushed into the open jaws of the clamps by spring actuated fingers 72 and 73 carried by the ejector. The fingers 72 and 73 are triangular in shape and are fixed to spring arms 74 and 75 attached to the inner face of the discharge plunger by rivets or the like 76. Due to the spring arms, the fingers tend to move outwardly through slots 77 and 77' in the lower end of the discharge plunger, but are normally held within the plunger by a ring 78 encircling the plunger and supported above the turntable by a bracket 79 suspended from the top frame member 4. As the plunger moves downwardly through the ring, the fingers are released and slide in the mandrel until they spring outwardly through slots 80 and 81 in the mandrel to extend the sides of the bag outwardly into the clamps, as best shown in Fig. 8. When the plunger is returned to its normal position, the upper inclined faces of the fingers engage the ring and are again retracted into the discharge plunger.

The clamps 70 and 71, as best illustrated in Fig. 16, each comprises a gear 83 provided with an integral side flange 84 on its inner face and carried by the flange in a hollow, cone-shaped extension 85 having slots longitudinally of its center as at 86 to admit the edges of the bag into the jaws contained within the extension. The jaws 87 each comprises semicone-shaped members 88 and 89 provided with gripping faces 90, the jaw members being normally retained in the rear, enlarged portion of the cone-shaped bore in the extension 85 and urged apart by an expansion spring 91, the opposite ends of which are mounted in recesses 92 in the adjacent faces of the jaws.

The jaws are held from rotation within the cone extension by pins 93 and 93' extending through slots 94 and 94' cut longitudinally in the extension at right angles to the slots 86 so that the jaws can slide longitudinally in the bore but are retained in alignment with the bag admitting slots 86. The jaws are urged into clamping position in the restricted end of the bore by a spring 95 contained within the bore of the gear and coiled about the shaft 96 slidably mounted in and upon which the gear 83 is rotatably mounted; one end of the spring bearing against the hub of the gear wheel and the other against a head 97 on the shaft. The plunger is normally retained from engagement with the jaws by a cam 99 (Fig. 10) carried on the forward ends of a rail 100 or 101 adjacent to the bag seat 69 so that when the clamps are in bag-receiving position the inclined faces 70 of the cams engage the inner faces of disks 104 fixed to the free ends of the shafts 96, as shown in Fig. 10, and hold heads 97 away from the jaws.

The gear wheels 83 are rotatably mounted in bearings 106 and 107 and are retained therein by washers 103 on the shafts and by pins 109 extending through the shaft and engaging the side of the bearing.

The bearings 106 and 107 are fixed to the arms 110 and 111 which slide on rails 100 and 101 and constitute forward guide arms for a carriage 112 which is also provided with laterally extending guide arms 114 and 115 on its rear end (Fig. 2).

The guide arms 110-111 are provided with lips 116 which extend over the tops of the rails 100 and 101 so that the carriage may slide along the rails longitudinally of the machine and away from the bag seat 69, as hereinafter described. The rails 100 and 101 are mounted longitudinally of the machine, one at each side of the seat 69 and fixed at their ends to the end frame members by bolts 117 (Figs. 1 and 2).

Fixed to the inner sides of the rails 100 and 101 and in mesh with the clamp pinions are rack bars 118 and 119 so that as the carriage is moved along the rails the pinions will rotate on their shafts, rotating the clamps and rolling the open edges of the sack in a roll 120 (Figs. 13, 14 and 15) preparatory to the sewing operation.

Actuation of the carriage is effected by the following mechanism:

Meshing with the gear wheel 121 on the shaft 62' is a gear wheel 122 (Fig. 2) rotatably mounted on a stub shaft 122' fixed in the intermediate frame member 6. The gear wheel 122 carries a horizontal gear segment 123 on its upper face which meshes with bevel gears 124 and 125 carried at opposite sides of the axis of the wheel 122 on a shaft 126 rotatably mounted in bearings 127 and 128 in arms 129 and 130 carried by the respective side frames 3 and 2. Pinned to the shaft 126 is a gear wheel 131, driving a gear wheel 132 rotatable on a shaft 133 mounted on the arm 130 longitudinally beneath the carriage herefore described.

The gear wheel 132 meshes with an elongated pinion 134 (Figs. 1 and 2) rotatably mounted in bearings 135 and 136 on the carriage 112. The pinion 134 is internally threaded to receive a threaded rod 137, one end of which extends through the pinion, the other end being mounted in a boss 138 on the rear end of frame 5 and held against rotation by a pin 139 which extends through the boss and through the rod. Therefore, when the

gear 122 is rotated by the gear wheel 121, the gear wheel 122 carries the segment 123 into engagement with the bevel gear 124, rotating the bevel gear to rotate the gear wheel 131 through its shaft 126.

The gear wheel 131 meshing with the pinion 134 drives the pinion, causing it to thread itself rearwardly on the threaded shaft 137 to draw the carriage rearwardly of the machine 10 on the rails 100 and 101. This movement of the carriage carries the clamps away from the cams 99, releasing the shafts 96 which are then thrust inwardly by springs 95 to advance and close the jaws 94 on the parts of the bag 15 within the clamp slots, so that when the bag is moved off of the seat 69 it is suspended from the clamps 70 and 71 and the gear wheels 83, rolling on the fixed racks 118 and 119, rotate the clamps to roll the open end of 20 the bag and carry it to a sewing mechanism. At the time the carriage aligns with the sewing mechanism hereinafter described, the segment 123 has moved from engagement with the gear wheel 124 and further movement of the carriage stops until the tying operation is completed.

The tying or sewing mechanism (Figs. 10 to 15 inclusive) comprises a helical-shaped needle 141 which is threaded through and 30 over the roll of the bag by the following mechanism:

The needle 141 is carried upon the end of an elongated pinion 142 threaded on a screw shaft 143 that is fixed in a bracket 144 on the 35 side frame 2, so that when the pinion is rotated, the needle is rotated and fed longitudinally of the screw shaft to thread it through a spiral opening 83' in the gear wheel 83 of the extension 85 of the clamp 71 and 40 through the bag. The pinion 142 is rotated by a segment 145 also carried on the gear 122 and meshing with a bevel gear wheel 146 fixed on a shaft 147 extending across the machine and mounted in bearings 148 and 149 in 45 the respective sides of the frame.

The shaft 147 (Figs. 1 and 2) carries a sprocket wheel 150 which, through a chain 151, drives a sprocket wheel 150' on a shaft 152 carrying a gear wheel 153 journaled in 50 the side frame 2. The gear wheel 153 meshes with and rotates the pinion 142 which carries the needle 141. As the needle nears the end of its forward travel, a spring clamp 155 (Figs. 17, 18 and 19) fixed in a slot 156 55 in the end of the needle by rivets, as at 157, engages a string holding device to open the spring clamp so that it may receive the string. The clamp comprises a slotted head 158 having a cam-shaped lower portion 159 engageable with the string holding device to raise the clamp against its spring tension into position to engage the string 160. The string holder, which retains the string in 60 position to be gripped by the needle, comprises a longitudinally grooved cylinder 161

slidably keyed by a pin 162 on a shaft 163 supported in bearings 164 and 165 on the carriage 112, the cylinder being normally urged against the bearing 165 by a spring 161' coiled about the shaft and bearing at its opposite ends against the cylinder and against a button 163' on the end of the shaft. Projecting radially from the periphery of the cylinder, between the grooves 161'' are pairs of pins 166 for guiding the string across 70 the grooves in position to be engaged by the needle clamp, so that on its return travel the needle may pull the loose end of the string from between the pairs of pins at the left of the needle (Fig. 17), the reel end of the 75 string being retained between the pair of pins at the right of the needle. After the needle clamp receives the string in its slot, the needle continues to move forward until the cam 159 leaves the string holding device and the clamp drops into its groove in the needle and holds the string. On return of the needle the cam 159 again contacts the string holder, but on this return movement causes the holder to move along the shaft against the tension of spring 161', thereby avoiding freeing of the string clamp and release of the string.

At this point, mechanism for forming and tying ears on the corners of the bag come 80 into operation. Mounted on parallel spaced shafts 171 and 172 (Figs. 10 and 11) rotatably carried in a frame 173 supported by the rails 100 and 101 above and in line with the needle are disks 174 and 175. Attached 85 to the peripheries of said disks by rivets 176 are curved arms 177 and 178 (Fig. 12), each comprising flat spring members 179 and 180 provided on their free ends with gripping jaws 179' and 180' which are normally open to receive the string as presently described, the free ends of the arms extending away from the disks a sufficient distance to enter between the spirals of the needle, as shown in Fig. 13, when the disks are rotated. Rotation of the disks is effected by mechanism comprising a gear segment 183 (Fig. 2), also fixed to the upper face of the gear wheel 122 and which meshes with a bevel gear wheel 184 mounted on a tubular 100 shaft 185 sleeved upon the shaft 147 between the bevel gear wheels 146 and 170. Also fixed to the shaft 185 is a sprocket wheel 186 which drives a sprocket wheel 187 on a shaft 188, rotatably mounted in the frame 105 173 through a chain belt 189. Fixed on the shaft 188 is a worm gear 188' that drives a worm gear 190 on the disk shaft 172 to drive the disk 175. Disk 174 is rotated in the opposite direction through a gear wheel 181 110 fixed to the shaft 172 in mesh with a gear wheel 182 on the shaft 171.

Rotation of the disks 174-175 causes the curved arms 177-178 to move downwardly and outwardly in opposite directions within 115

120

125

130

the needle spiral and, at the end of the movement, to slidably raise their free ends so that the jaws on the ends of the arms receive convolutions of the needle.

5 At this point the segment 183 moves away from the gear wheel 184 and movement of the arms is stopped as the needle is withdrawn, due to the fact that the segment 169 on the gear wheel 122 has engaged the bevel gear wheel 170 on the shaft 147 opposite to the bevel gear wheel 146, and rotates the shaft in an opposite direction.

As the needle is withdrawn, the string is threaded in loops through and over the roll 120 at the top of the bag and is drawn through the jaws 179' and 180' and over the ends of the arms, as shown in Fig. 14. After the needle is withdrawn and the jaws have gripped the string, as described, the arms 20 are returned to their former position by a segment 192, also on the gear 122, coming into engagement with a bevel gear 193 on the tubular shaft opposite and facing the gear 184, so that the rotation of the shaft is reversed 25 and the disks are returned. On return travel of the disks, the arms 178-179 bear against a wheel 194 pivoted on the frame 173 between the disks, which closes the jaws to grip the string and draw the ends of the 30 string through the loops through which the arms have projected during forward movement of the disks, the segment 192 remaining in engagement with the bevel gear wheel long enough for the arms to pull the loops 35 up tight about the roll. After this operation the gear segment 123 on the gear wheel 122 comes into engagement with the bevel gear wheel 125 on shaft 126 to drive the shaft in a reverse direction to that of its initial 40 movement, rotating the pinion 139 in a reverse direction to return the carriage for another bag. As the carriage starts to return the disks 104 on the clamp shafts engage the inclined faces 195 (Fig. 10) of pivoted release arms 196 and 197 carried by the rails 100 and 101, shifting the jaws against the tension of their springs and permitting them to drop the bag. The bag in dropping from the machine down a chute 198 (Fig. 1), 50 pulls the string over a V-shaped knife 199 (Fig. 9) mounted on one of the arms of the bearings 164-165 on the carriage 112 to sever the string and free the bag.

The cam arms 196 and 197 are pivoted as 55 at 200 to the rails and held in functional position against stop pins 201 by springs 202, one end of each spring being fastened to a hook 203 on the arm and the other to a pin 204 on the rail. When the carriage 60 moves in a forward direction (left to right in Fig. 10) the disks strike the upper rear edges 205 of the arms and rock them out of the way under the tension of the springs 202 which, after the disks have passed, return 65 the arms to their former positions so that

the gripping effect of the jaws is not interfered with, but as the carriage returns, the arms are held in functional position by the stop pins and the disks strike the inclined faces on the arms, forcing the disks and their 70 rods outward to cause the jaws to release.

On the next forward movement of the carriage, the string gripping cylinder is advanced to carry the string across the parts of the needle by the following mechanism: 75

The shaft 163 (Fig. 17) extends beyond the bearing 164 and fixed on the extension of the shaft is a ratchet wheel 208, operable by a ratchet pawl 209 pivoted to an arm 210 carried upon a tubular shaft 211 sleeved on 80 the end of the shaft 163 and held thereon by a collar 212 formed at the end of the shaft.

The tubular shaft 211 carries a pin 214 which is received in a spiral slot 215 in a sleeve 216 carried on a bracket 217 on the 85 rail 100, so that when the carriage moves forwardly the tubular shaft carrying the ratchet arm moves within the sleeve 216 and the pin 214 traveling in the slot 215 rotates the shaft to cause the ratchet to advance the 90 grooved cylinder and position the string to be engaged by the needle as before. The string is carried on a reel 218 mounted on the under side of the carriage and is guided to the cylinder over a roller 219. 95

Assuming the parts to be constructed and assembled as described, the operation is as follows:—

The pulley wheel 22 is constantly rotated on the shaft 18 because of its connection with 100 the source of power (not shown) through the belt 21.

An operator slips a bag over one of the mandrels 13 so that it is supported at its lower end on the table 17 and presses on the button 23, shifting the rod 36 to carry the clutch member 25 into mesh with the clutch member 26 on the pulley 22 and simultaneously releasing the bevel gear wheel 28 from the hook 40. The shaft 18 is thereupon rotated, rotating the bevel gear wheel 28 and the shaft 29, the latter carrying with it the segmental gear wheel 31. When the teeth on the gear wheel 131 reach the pinion 32 the latter is rotated, rotating the shaft 33 and the pinion 34. The pinion 34 being in mesh with the teeth on the periphery of the turntable 10, the turntable is carried about for a part revolution represented by the teeth of the gear wheel 31 and until the mandrel carrying the bag is brought beneath the spout 16 when flour is released through the spout to fill the portion of the bag projecting beneath the mandrel and fill the mandrel to the proper depth. When the turntable has remained 125 stationary a sufficient length of time to permit the mandrel to fill, the toothed portion of the gear wheel 31 again comes into mesh with the pinion 32, and the pinion shaft 33 and pinion 34 are again rotated to advance 130

the turntable another step, this second movement carrying the mandrel (just mentioned) beneath the packing plunger 43 which is timed to be lowered into the mandrel and pack the flour therein as soon as the mandrel assumes the packing position; actuation of the plunger being effected by lowering of the elongated pinion 40 by its rotation upon the screw 53 under influence of the gear wheel 59 on the shaft 58 driven by the pinion 57 meshing with the segmental rack 61 on the horizontal gear wheel 62 driven from the gear wheel 55 which is also fixed on the shaft 25 and operable from the main shaft 18 through the bevel gear mechanism heretofore described. As soon as the plunger has been lowered and has performed its packing operation the elongated pinion is elevated to lift the plunger out of the mandrel by engagement of the pinion 57 by a segmental rack 56 on the shaft 55, the racks 56 and 57 operating alternately and in opposite directions to raise and lower the pinion at timed intervals.

When the packing plunger is operated as described, and has left the mandrel for its return movement, the segmental gear wheel 31 will have again engaged the pinion 34 on the shaft 33 and the turntable will be advanced another step, this movement carrying the bag off of the table 17 onto a platform 69 suspended from the vertically movable arm 66 that is connected with the elongated pinion 49. At this point the pinion 57 is again engaged by the segmental rack 61 and rotated to lower the elongated pinion, the plunger 64 and the platform 69, the table remaining stationary so that the bag and its contents are moved off the mandrel to the position indicated in Fig. 8. The clamps 70 and 71 being located at this extruding position, the bag is moved down between them so that when the packed part of the bag has passed the clamps, opposite edges of the bag will be positioned between the jaws of the clamp, this positioning being facilitated by the fingers 72 and 73 connected to and forming parts of the extruding plunger structure. The clamps 70 and 71 being mounted on the platform 112 and the platform 112 being timed to move rearwardly when the extruding plunger has completed its downward stroke, the clamps are moved back, releasing the contained grippers because of the release of the disk 104 from the cams 102, and the edges of the bag are now held firmly in the clamps, the grips of which are sufficiently strong to sustain the weight of the packed bag; rearward movement of the platform inducing rearward travel of the clamps which, upon such movement, are rotated because of the engagement of their pinions 83 with the stationary racks 118 and 119, and this rotation of the clamps winding the top, loose portion of the bag so that the mouth of the bag is folded over to close the same. When the mouth of the bag

has been closed as described, the clamps come to a halt beneath the sewing mechanism.

As previously mentioned in description of detail structure, movement of the platform 112 is effected by rotation of the pinion 139 ⁷⁰ that is anchored to the platform along the contained stationary screw 137, the pinion being rotated by the meshing gear wheels 132 and 131, the latter on the shaft 126 which receives its reverse motion for effecting backward and forward movement of the platform through the bevel gears 124 and 125, operable by the gear segment 123 on the wheel 122 driven from the shaft 121 which in turn is driving from the gear wheel 55 on the shaft 29 (heretofore mentioned).

As soon as the bag comes to rest at the needle position, the needle starts its convolute travel through the lapped mouth of the sack, the rotary and longitudinal movement of the ⁸⁵ elongated pinion 142 being effected through the mounting of the pinion on the screw 143, and operation of the pinion through the gear wheel 152 operable from the sprocket wheel 153, operable by the belt 151 from the sprocket ⁹⁰ wheel 150 by the sprocket wheel 149 on the shaft 147 carrying the gear wheel 146 which is, in turn, operated by the horizontal gear segment 145 on the upper face of the gear wheel 122 heretofore mentioned.

As the needle reaches the end of its convolute travel, its point contacts the string holding cylinder, opening the clamp on the end of the needle to permit the needle to grip the string so that when the needle starts its backward travel it may pull the string with it through the lapped portions of the bag. When the needle has gripped the string, however, there is an interruption of travel, and during this interruption the disks 174 and ¹⁰⁰ 175 are rotated oppositely because of rotation of the gear wheels 181 and 182 through their inter-meshed engagement, and through operation of the worms 190, 189, the shaft 188, belt 189, sprocket wheel 186, tubular shaft 185, ¹⁰⁵ bevel gear wheel 184 and the horizontal gear segment 183 on wheel 122; this movement of the disks carrying the spring arms 179 and 180 oppositely and outwardly beneath two convolutions of the needle and positioning ¹¹⁰ the fingers 179' and 180' over the next outer convolution. At this point movement of the disks is interrupted and travel of the needle is reversed, the clamp on the free end of the needle pulling the string with it so that as the needle unwinds from the overlapped mouth of the bag, the string is drawn through it to form the loop or stitch, reverse movement of the needle pinion being effected by the same mechanism heretofore described except ¹¹⁵ that the bevel gear wheel 170 on the opposite end of the shaft 146 is engaged with the segmental rack 123 which drives the gear wheel 47 and the parts in train with it, reversely to the travel upon which the needle pinion is ¹²⁰ ¹²⁵ ¹³⁰

advanced. As soon as the needle has been withdrawn from the bag, the travel of the disks 174 and 175 is reversed, the bevel gear wheel 193 of the tubular shaft 185 now meshing with the segmental rack 192 on the wheel 22. When the gears start their backward movement the spring arms engage the wheel 194, press the fingers of the arms together and cause them to grip the string so that when the arms are pulled back through the convolutions of the string, the ends of the string are pulled with them and continuous movement of the disks drawing the ends of the strings tight to tighten the stitches and bind the edges of the string between the last two stitches. When the thread has been drawn tight and tied as described, backward movement of the disks is interrupted and the platform 112 again moves forwardly, this forward movement of the platform causing the clamps 70 and 71 to rotate through their gear and rack connections and twisting the corners of the bag.

After the platform has moved a short distance the collars 104 on the ends of the clamps 70 and 71 engage the cams 195 and 197 which draw the collars and the shaft 96 outwardly to spread the clamp jaws and release the bag. The bag now falls into the chute 198 to be carried out of the machine, the weight of the bag pulling the ends of the string from the clamp fingers of the tying disks and the reel end of the string passing over the knife 199 to sever the string. Continued forward movement of the platform 112 rotates the collar 211 to advance the string holding cylinder so that upon the next operation of the needle it may pass beneath the string and grip the same as heretofore described.

While I have followed the movement of one bag through the machine, other duplicate operations are at the same time being performed on succeeding bags, the packing plunger operating on a succeeding bag while the extruding plunger is operating on a preceding one, and the operation being repeated as described for each oncoming bag.

What I claim and desire to secure by Letters-Patent is:—

1. In a machine of the character described, a string holder, a convolute needle comprising means for gripping a string, and means operating the needle in one direction to penetrate the bag and in reverse direction to draw the string through the bag in a convolute path.

2. In a machine of the character described, a convolute needle comprising a string clamp, rotatable and longitudinally movable means to advance and return the needle, means actuating the clamp at one end of the needle travel to grip a string, and tying members operable within some of the convolutions of the string to draw the ends of the string therethrough.

3. In a machine of the character described,

a convolute needle having a normally closed, spring jaw at its free end, rotatable and longitudinally movable means for advancing and returning the needle, and a string holder at one end of the needle path engageable by the needle to open the jaw to receive the string.

4. In a machine of the character described, a convolute needle having a slot in its free end, a jaw spring mounted on the needle, yieldingly located in said slot, having a string slot and a cam, means for advancing and returning the needle and a member at one end of the needle path engageable by the jaw cam upon advance of the needle, to open the jaw to receive a string.

5. In a machine of the character described, a convolute needle having a jaw at its free end, means for advancing and returning the needle, tying arms projectible through convolutions of the needle at opposite ends of the needle path, means on the arms for gripping a string delivered by the needle, and means for reciprocating the arms to finally withdraw the ends of the strings through convolutions thereof corresponding to said needle convolutions.

6. In a machine of the character described, a convolute needle having a jaw at its free end, means for advancing and returning the needle, tying arms projectible through convolutions of the needle at opposite ends of the needle path, means on the arms for gripping a string delivered by the needle, means for reciprocating the arms to finally withdraw the ends of the strings through convolutions thereof corresponding to said needle convolutions, and means operable on said arms during their return movement to maintain the gripping action.

7. In a machine of the character described, a convolute needle having a jaw at its free end, means for advancing and returning the needle, tying arms projectible through convolutions of the needle at opposite ends of the needle path, comprising spring fingers for receiving a string between them, means for reciprocating the arms and a pressing member engageable by the arms on their return travel to maintain the fingers in their gripping relation.

8. In a machine of the character described, a convolute needle having a jaw at its free end, means for advancing and returning the needle, reversely rotatable disks, tying arms on said disks having free ends projectible through convolutions at opposite ends of the needle and comprising spring fingers normally open to receive a string delivered thereto by the needle, and a roller engageable with the arms on their return travel to maintain gripping relation of the fingers.

9. In a machine of the character described, grippers and means for rotating the grippers to turn a fold on a bag, a convolute needle

having a jaw at its free end for gripping a string, means for advancing and returning the needle, tying members engageable with the string and movable through convolutions 5 thereof formed by the needle, and means for opening the grippers to release the bag.

10. In a machine of the character described, spaced racks, a reciprocating platform, gear wheels journaled on the platform and engaging 10 the racks, the gear wheels having slotted extensions, spaced jaws keyed for longitudinal movement within the extensions, means yieldingly urging the jaws to closed relation, means normally retaining the jaws open, 15 means for passing a bag to project portions thereof into said slots and between the jaws, means for releasing the jaws to grip the bag, a convolute needle having a gripping jaw on its free end, means for advancing and returning 20 the needle, means for presenting a string to the needle jaw, means for tying the ends of the string, and means for cutting the string.

11. In a machine of the character described, spaced grippers adapted for engaging a bag, 25 means for conducting the grippers from a bag-receiving station to a bag-sewing station, means for actuating the grippers to turn a fold on a bag, a convolute needle movable across the line of travel of said grippers, 30 and means for rotating the needle during its travel.

12. In a machine of the character described, spaced grippers adapted for engaging a bag, means for conducting the grippers from a

bag-receiving station to a bag-sewing station, 35 means for actuating the grippers to turn a fold on a bag, a convolute needle movable across the line of travel of said grippers, means for rotating the needle during its travel, and tying members rotatable on axes 40 transverse to the needle axis.

13. In a machine of the character described, spaced grippers automatically operable to grip and support a bag, means normally restraining the grippers, means for feeding a 45 bag to the grippers, means for shifting the grippers to release the grippers and effect transfer of a bag to a sewing station, means for operating the grippers to turn a fold on a bag, needle mechanism movable transversely 50 of the machine and comprising a convolute needle having a jaw for grasping a string, means for effecting opening and closing of the needle jaw, and means for rotating the needle during its transverse travel. 55

14. In a machine of the character described, means for turning a fold on a bag, a reciprocating needle carrier, means for imparting simultaneous longitudinal and rotary movement to said carrier, a convolute needle having one end attached to said carrier and having a jaw at its opposite end, and means for operating the jaw at the end of forward travel of the needle to effect application of a string to the jaw. 60

In testimony whereof I affix my signature.

JOSEPH R. BARTLETT.
